PRINTING APPARATUS AND METHOD
Ernst Daniel Nystrand, Green Bay, Wis., assignor to
Paper Converting Machine Co., Inc., Green Bay, Wis.,
a corporation of Wisconsin

Filed Dec. 3, 1963, Ser. No. 327,711
6 Claims. (Cl. 101—415.1)

This invention relates to printing apparatus, and, more particularly, to printing utilizing a flexible plate wrapped around a plate cylinder.

Thin flexible plates have been utilized before, but there has been a continuing problem of satisfactorily securing the plates against both deformation and movement. This invention provides apparatus which operates in a novel fashion to utilize movement to correct distortion and thus supply a faithful reproduction of the printed matter. The provision of apparatus that operates in a novel fashion to tension thin printing plates thus constitutes an important object of the invention.

Another object of the invention is to provide a novel combination of elements effectively utilizing such a flexible plate.

A further object of the invention is to provide a method for fastening of thin printing plates for rotary printing where the gap in printing between repeats is kept to a bare minimum.

Still another object of the invention is to provide a novel method of printing wherein the above-mentioned flexible plate is handled and used in a unique manner to provide superior printing.

The invention finds advantageous use in connection with high speed printing of office forms and like material. In such an environment, relatively short orders are common. Through the invention, quick and inexpensive replacement of the printing plates is facilitated, and this is especially important where the plate rolls are of relatively small diameter, i.e., carrying a single repeat of the order of 8"-11".

Other objects and advantages of the invention may be seen in the details of construction and operation set down in this specification.

The invention is explained in conjunction with an illustrative embodiment in the accompanying drawing, in which—

FIG. 1 is a fragmentary elevational view of a press utilizing the invention;

FIG. 2 is a fragmentary elevational view, partially in section, of the plate cylinder utilized in the invention;

FIG. 3 is a fragmentary perspective view of the printing plate prior to the installation thereof on the plate cylinder of FIG. 2;

FIG. 4 is an enlarged fragmentary end elevational view taken along the line 4—4 of FIG. 2;

FIG. 5 is a fragmentary sectional view taken along the line 5—5 of FIG. 4;

FIG. 6 is a fragmentary sectional view taken along the line 6—6 of FIG. 5;

FIG. 7 is a fragmentary sectional view taken along the line 7—7 of FIG. 5;

FIG. 8 is a fragmentary detail sectional view through a part of the plate cylinder of FIG. 2 and showing the first step of application of the printing plate of FIG. 3 to the plate cylinder of FIG. 2;

FIG. 9 is a fragmentary sectional view of the plate cylinder showing a modified form of construction;

FIG. 10 is a fragmentary perspective view of the end of one of the clamping bars employed in the plate cylinder; and

FIG. 11 is a view similar to FIG. 10 but of the other clamping bar used in the plate cylinder.

2

FIG. 12 is a fragmentary sectional view of a printing plate utilized in the invention.

FIG. 13 is a view similar to FIG. 12 but showing the printing plate with certain areas removed to leave standing cones.

Referring now to the drawing, and first to FIG. 1, the numeral 10 designates generally the frame for the press, which includes the usual side frames 11 and 12, suitably secured together by means of tie-rods 13, cross rods 14, etc., to provide a rigid structure. The frame provides journals for the various printing rolls, also in conventional fashion. As seen in FIG. 1, the web W proceeds around an idler roll 15 and then in wrapping engagement with an impression cylinder or roll 16, preferably constructed of steel. The web, after having passed around, i.e., traveled with, the impression cylinder 16, is conducted to additional finishing stations (not shown) for perforating, folding, etc.

When the web is on the impression cylinder 16, ink impressions or characters are transferred thereto from a blanket or transfer cylinder 17 which preferably is rubber-covered. The impressions are derived from a plate cylinder 18 which, like the cylinders 16 and 17, is journaled in the frame 10. From this, it will be understood that this showing is of offset printing.

To provide ink to the plate cylinder 18, the frame is equipped with a fountain roll 19 against which a doctor blade 20 operates, in conventional fashion. The ink from the fountain roll is transferred to the doctor roll 21 and thence to a longitudinally vibrating roll 22. The roll 22 in turn transfers its ink to distributing rolls 23 and 24, and these in turn relay the ink to a second vibrating roll 25. The ink is then transferred by means of form rollers 26 and 27 to the plate cylinder 18, more particularly, to the high point on the flexible plate covering, which can be better appreciated from a consideration of FIGS. 3, 12, and 13.

The printing plate is generally designated 28 and may include three layers of material. The first layer (to be positioned in contact with the surface of the plate cylinder 18) is a supporting surface and is constructed of a flexible, water-impervious plastic material 29. The outer layer 30 constitutes a water-soluble plastic material bonded to the inner layer 29 by means of a suitable adhesive binder 31. The plastic layer 30 has the property of being soluble in water until it has been exposed to light. Thus, in FIG. 13, it is seen that there are certain areas as at 30a which have been removed, leaving standing cones as at 30b. This is provided through the superposition of a negative or other light filter, wherein the light passing through the negative creates the cones 30b and upon subsequent washing with water, the areas 30a are dissolved. Thus, a suitable printing plate is provided which normally has a thickness of the order of 0.015—0.017". It will be apparent, however that other printing plates such as brass-backed rubber plates may be advantageously employed in the practice of the invention.

The plate cylinder 18 which supports the flexible plate 28 is seen in FIG. 4 to include a longitudinally extending recess 32 having a dovetail configuration in transverse section. The peak of the dovetail communicates with the periphery of the roll 18 as at 33, with the dovetail cross section being defined by outwardly converging walls 34 and 35. Hereinafter, when the term "first wall" is employed, it will refer to the wall 34, and the term "second wall" will refer to the wall 35.

Positioned within the longitudinally-extending recess 32 are two clamping members, a first clamping member 36 and a second clamping member 37 (see particularly FIG. 6). The second clamping member 37 bears against the second wall 35 and is urged thereagainst not only by the first clamping member 36 but also by the springs

38 which extend between the second clamping member 37 and the first wall 34, as illustrated in FIG. 6. The first member 36 is urged against the second member 37 by means of another group of springs 39 which also bear against the first wall 34, as seen in FIG. 7.

For the purpose of mounting the springs 38 and 39, the first clamping member 36 is provided with bores as at 40 and 41. The bores 40 are seen to extend through the generally rectangular-shaped first clamping member 36, while the bores 41 extend only partway through, as shown in FIGS. 6 and 7, respectively.

Additionally, the first clamping member 36 is equipped with a foot-like portion 42 which provides additional bearing between the first clamping member 36 and the base 32a of the recess 32. From a consideration of FIGS. 4 and 11, it will be seen that the second clamping member 37 is generally wedge or triangular-shaped in transverse section except for the portion 37a along one longitudinal corner being relieved to accommodate the foot-like portion 42. In this connection, refer to FIG. 3 where it is seen that the end portions of the plate 28 are folded downwardly as at 43. On a plastic plate, I have found that scoring as at 44 facilitates an even bend or fold.

In operation, a folded end portion defined by the end 43a and the transverse score line 44a is positioned between the second clamping element 37 and the second face 35, as appears in FIG. 8. Thereafter, the roll 18 is rotated in the direction of the arrow in FIG. 8 and the plate 28 may be "ironed" against the plate cylinder 18 by virtue of the forming rolls 26 and 27, after which the trailing end 43b is positioned between the first and second clamping elements 36 and 27, respectively (see FIG. 7).

Both clamping elements 36 and 37 are equipped with end slots as at 45 relative to element 36 (see FIG. 10) which permit its being pried against the urging of the springs 39 so as to permit insertion of the trailing end fold 43b.

With the clamping members arranged as seen in FIGS. 6 and 7, the springs 38 urge the generally rectangular-shaped first clamping member 36 against the end portion 43b and also against the second clamping member 37. In this connection, it will be appreciated that the foot-like portion 42 provides an advantageous additional bearing against the recess base 32a facilitating sliding movement of the member 36 so as to maintain the necessary clamping pressure.

The direction of rotation of the cylinder 18 is seen in FIG. 6, and it is seen there that the folded portion 43b provides the trailing edge, this being the portion inserted between the elements 36 and 37. This is particularly effective when the blanket or transfer cylinder 17 is slightly oversize, which might otherwise tend to pull out the plate 28 in the portion folded as at 43b. In actual practice, it is possible to fold the plate 28 a trifle short, so that a slight gap is maintained at 43b even after the plate is inserted.

It will be seen that the first clamping member 36 is generally a parallelepiped, including opposed 60° angles, with the upper surface as at 46 (see FIG. 8) being ground to the curvature of the plate cylinder 18. Longitudinal movement of the first and second members 36 and 37 is restricted by means of straps or plates 47 (see FIGS. 2 and 4) which are suitably anchored by means of bolts 51 at the two ends of the plate cylinder 18.

It will be appreciated that for suitable repeats it is necessary to print over the surface designated 46 in FIG. 8. Through the invention, a slight sliding movement of the element 36, necessary for holding the tail 43b of the printing plate 28, does not appreciably alter the height, i.e., radial distance, of the surface 46. The base of the dovetailed surface 32a is at a right angle to a center line drawn from the middle of the surface 46 as in FIG. 8. Theoretically, the base 32a of the dovetail and the touching portions of the elements 36 and 37 conform to an arc of curvature, the center of which corresponds to the center of

the plate cylinder 18. In actual practice, the planar surface shown approximates this:

In the illustration given, for a 11" repeat (plate cylinder circumference), the foot-like portion 42 is a 30° projection, with the length of the foot being of the order of $\frac{5}{64}$ ".

With the construction shown, it is possible to advantageously utilize small diameter plate cylinders, i.e., of the order of 8 $\frac{1}{2}$ to 11 inches, and thus print a web with a single repeat, and a plate can be changed herein in about one minute. Also, I find that the use of the offset arrangement pictured in FIG. 1 gives superior printing and with about one-half as much ink as the direct impression technique normally employed.

The advantageous sliding movement of the members 36 and 37 maintains optimal pressure on the ends of the thin printing plate, minimizing distortions, and this sliding movement may be enhanced through the use of molybdenum disulfide tape on the undersides of the elongated members 36 and 37.

In FIG. 9, a modified form of construction is seen wherein the plate 28 is seen to have its tail portion 143 adhesively secured by means of adhesive 149 to the upper surface of the clamping bar 36 which is carried by the plate cylinder 18. It will be noted that in all of the illustrations a small gap G, as designated in FIG. 9, occurs, and this is tolerable since in the printing provided by the invention there are small spaces provided between adjacent repeats. It will be appreciated that with the plate mounting of the invention the gap between printing repeats is kept to a bare minimum, occurring only at the apex of the clamping element 37.

While in the foregoing specification a detailed description of an embodiment of the invention has been set down for the purpose of explanation, many variations in the details herein given may be made by those skilled in the art without departing from the spirit and scope of the invention.

I claim:

1. A printing plate cylinder, comprising an elongated cylindrical roll having a longitudinally extending dovetail-like recess equipped with a bottom wall and side walls converging to provide a constricted peripheral opening and adapted to secure the ends of a flexible printing plate, first and second elongated clamping members in said recess in side-by-side relation, and spring means in said recess urging said members toward one of said walls, said spring means including two sets of springs positioned in said recess, one of said sets of springs extending between the other converging wall and said first member to urge said first member toward said one wall, the other set of springs extending between said other wall and said second member to urge said second member against said one wall, said first member being equipped with transverse openings with said other set of springs extending therethrough.

2. The structure of claim 1 in which said first member is equipped with an integral foot portion in contacting relation with the base wall of said recess.

3. A printing plate cylinder, comprising a roll having a longitudinally-extending, dovetail recess in the periphery thereof, a first elongated member in said recess and having generally a rectangular shape in transverse section, a second elongated member in said recess and having generally a wedge shape in transverse section, a first plurality of springs in said recess urging said first member against said second member, a second plurality of springs in said recess urging said second member against the wall of said recess, said first member being equipped with transverse openings with said second plurality of springs being housed therein, each member being adapted to bear against an end of a flexible printing plate, and slot means at the end of each member for lever engagement to overcome said springs.

4. The structure of claim 3 in which said first member is equipped with foot means underlying said second mem-

ber and contacting the base of said recess to facilitate sliding movement of said first member, whereby clamping pressure on said plate is maintained.

5. In a printing press, a frame, an impression roll journaled in said frame, a transfer roll journaled in said frame for transferring ink impressions to a web traveling on said impression roll, a plate roll journaled in said frame for delivering ink impressions to said transfer roll, and roll means in said frame for delivering ink to said plate roll and for pressing the surface of said plate roll, said plate roll comprising a roll having a longitudinally-extending dovetail recess in the periphery thereof, a first elongated member in said recess and having generally a rectangular shape in transverse section, a second elongated member in said recess and having generally a wedge shape in transverse section, a first plurality of springs in said recess urging said first member against said second member and away from one of said dovetail walls, a second plurality of springs in said recess urging said second member against the other dovetail wall and away from said one dovetail wall, said first member being equipped with transverse openings with said second plurality of springs being housed therein, each member being adapted to receive an end of a flexible printing plate, slot means at the ends of each member for lever engagement to overcome said springs, and a flexible plate mounted on said plate roll with the ends thereof in clamping relation with said members.

6. A printing plate cylinder, comprising a roll having a longitudinally-extending, dovetail recess in the periphery thereof equipped with a bottom wall and side walls converging to provide a constricted peripheral opening and adapted to secure the ends of a flexible printing plate, a

first elongated member in said recess and having a generally rectangular shape in transverse section, a second elongated member in said recess and having a generally triangular shape in transverse section, said second member being in confronting relation with one of said side walls and said first member being in confronting relation with the other of said side walls, transverse passage means in said first member and spring means in said passage means extending between said second member and said other wall, and additional spring means separate from the first-mentioned spring means interposed between said other wall and said first member whereby said members are independently manipulable to secure in independent fashion the said flexible printing plate ends.
